UNITED STATES PATENT OFFICE

HAROLD R. KIRKLAND, OF SOUTH ORANGE, NEW JERSEY

DESIGN FOR AN ANNUNCIATOR OR SIMILAR ARTICLE

Application filed September 5, 1930. Serial No. 36,880. Term of patent 7 years.

To all whom it may concern:

Be it known that I, HAROLD R. KIRKLAND, a citizen of the United States, residing at South Orange, Essex County, State of New Jersey, have invented a new, original, and ornamental Design for Annunciators or Similar Articles, of which the following is a specification, reference being had to the accompanying drawings, forming part thereof.

Fig. 1 is a face view of an annunciator showing my new design.

Fig. 2 is an edge view.

What I claim is:

The ornamental design for an annunciator or similar article, substantially as shown.

HAROLD R. KIRKLAND.
